UNITED STATES PATENT OFFICE.

ROLAND ROLF RICHARD, OF KYNUNA, NORTH QUEENSLAND, AUSTRALIA.

WINDMILL.

Application filed November 13, 1922. Serial No. 600,711.

To all whom it may concern:

Be it known that ROLAND ROLF RICHARD, a subject of the King of Great Britain, residing at Kynuna, in the State of North Queensland, Australia, has invented certain new and useful Improvements in Windmills, of which the following is a specification.

This invention refers to windwheels of the horizontal type and consists of constructional improvements designed with the object of attaining lightness consistent with necessary strength and to provide automatic means for retarding revolution of the wind wheel during excessively strong winds.

A further object of the invention is to provide means for enabling the wind wheel to revolve during wind of low pressure and for this purpose the wind wheel is mounted on a float supported in a liquid such as oil or water or oil and water contained preferably in a cistern whereby said float supports the weight of the wind wheel and thereby reduces friction.

In the accompanying drawings Fig. 1 is an elevation (broken) of the mill, in which the float is employed.

Fig. 2 a vertical section of the windwheel, and

Fig. 3 a plan.

Fig. 4 is an enlarged vertical section (broken) through parts of Fig. 2, and

Fig. 5 is a detail vertical section through the windwheel.

Figs. 6 and 7 are enlarged detail views (broken) of the crank gear.

Fig. 8 is a detail of a modification of the brake gear.

According to this invention, the sails or vanes 1 hang vertically from horizontal circular rims 2, being set at the desired angle and joined at intervals by bracing sheets 3 and joined at intervals by bracing sheets 3 (Figs. 1 and 5) of metal or other suitable material set with their edges presented outwards and inclined upwards spirally so that the pressure on the lower part of the vanes will be transmitted upwards to the rims 2 without twisting the vanes 1 or otherwise damaging same.

The upper rims 2 are supported by radial arms 4, 5, suitably joined preferably to form cantilever trusses, the arm 4 being provided with a circular rail 6 (Figs. 2 and 3) located immediately above stationary brake blocks 7 (Figs. 1 and 2) which are attached preferably to the rim of a cistern 8. A space

provided between the circular rails 6 and the brake blocks 7 is such as to allow contact of these parts under extra high speeds in high winds.

It will be evident without illustration that the rail 6 might be fixed to the top of the cistern and the brake blocks to the arms of the wind wheel.

The brake blocks 7 as illustrated, are hinged as at 9 and one or more are provided with handles 11 so that they may be applied by hand when it is necessary to stop the windwheel rotating. The handle may be fixed by means of a bolt 12 passed through a rack bar 13. The arms 4 are attached to a central float F located in the cistern 8 containing water or oil or water and oil and supported on the frame and said float F is formed with a central sleeve or shaft 14 provided with bearings 15, 16, that rotate around a hollow stationary shaft or axle 17.

The bearings 15, 16 which may be either ball, roller or such other kinds as are in general use are connected together by means of rods 18 to hold them in position relative to one another and enable them being withdrawn through the sleeve 14 and they are also provided with set screws 19 which pass through the sides of the sleeve thus enabling said sleeve and windwheel to be centralized and rotate evenly around its axis. The rods 18 are screwed or otherwise fixed to the lower bearings 16 and passed through holes in the upper bearing 15 and secured by nuts. 90

To the upper end of the sleeve 14 is fixed a boss 20 into which is fixed the central rotary shaft 21 of the windwheel which extends downwardly through the fixed shaft 17 and suitable bearings on the frame and 95 is provided for instance with a crank disc 22 (Fig. 1) to the crank pin 23 of which is connected a connecting rod 24 operating a balanced lever or "bob" 25 connected with a pump rod 26.

With this construction Fig. 6, it is necessary that the bearing portion of the crank pin 23 be partly spherical and engage a corresponding seating 63 located in a container 64 for lubricant, the boss 65 of the crank disc also dipping into the container. The other end 66 of the rod 24 is bent down so that the pivot 67 on which it turns can be immersed in a container 68 filled with lubricant and fixed to the balance bob 25.

To the top of one of the arms 5 or else to an extension of the boss 20 a T-shaped crank

pin 27 is fixed which is provided with a connecting arm 28 which receives reciprocating motion and may be connected for instance to a bell-crank 29 mounted on a tower 30 and connected to a pump rod or vertical arm 31 to convey power to a lower level.

Owing to the crank pin rotating in a horizontal plane and the bell crank rocking in a vertical plane, provision must be made at 10 the connections to obtain smooth motion.

As illustrated in Fig. 7 the crank pin 27 works in a bearing 69 in an oil well 70 protected from rain by a cover 71 on the arm 28 and said pin has a collar 72 engaging a recess in the bearing to prevent the pin 15 rising.

The connecting arm 28 is bent down at its ends 73, 74 and one end 73 is connected to a cross head 75 on the pin, the limbs of 20 said head being journaled in bearings 76 in the well.

The other bent end 74 of the arm 28 is similarly connected with the cross head 77 of a vertical pin 78, the limbs of said head 25 being mounted in bearings 79.

The vertical member of the bell crank is 30 hollow and acts as a bearing for the pin 78 which is provided with a collar 80 engaging a recess in said member. The latter is provided at the top with an oil well 81 protected by a cover 82 on the arm 28.

The pivot 83 of the bell crank is fixed in the walls of an oil well 84 fixed on the tower 30, and it engages bearings 85 on the 35 bell crank, which is provided with a cover 86 to protect said well.

The end 87 of the bell crank is bent and 40 its pivot 91 is fixed in a cup 88 of the pump rod 31 which cup holds a lubricant and is protected by cover 89 fixed to the bell crank. The bell crank is provided with a bearing 90 which oscillates around its pivot 91.

The float F is provided on its side with 45 small metal blades 32 (Fig. 2) bent outwardly to propel the water or oil towards the wall of the cistern during strong winds, thus allowing the float F and the whole of the windwheel to descend until the circular rail 6 is brought into frictional contact with 50 the brake blocks 7.

Alternatively as shown in Fig. 2 blades 61 may be pivoted to the arms 5 and normally held out of contact with the liquid by a spring 62 but which by centrifugal 55 action under high speed would dip into the liquid and retard the speed of the wind wheel.

The float F may be conical or of other 60 suitable shapes and may be open at the top, or closed theret and open at the bottom or it may be closed at both ends. When stability and smooth running are essential it would be so designed that its centre of 65 flotation is near or above the centre of gravity of the whole windwheel and the

centre of wind pressure would be approximately opposite the lower bearing 16 which would thereby become the centre of resistance thus minimizing the bending moments on the fixed shaft or axle 17 and the rocking of the windwheel during irregular wind currents.

Owing to this and the fact that the arms, 4, 5, upper rims 2 and other parts of the windwheel are necessarily above the float F 75 and only the lower rim 52 and part of the vanes 1 can project below the float F, the float is best made in the shape of the frustum of a cone, (inverted) in order to raise 80 the centre or flotation.

To prevent friction and consequent loss of power all stay bolts and other fastenings are located inside the float and only the sheet metal forming the outer skin being 85 in contact with the water in which it is suspended.

The float F may be constructed in a variety of different ways. For instance it 90 may be made entirely of sheet metal of sufficient thickness to stand the pressure of the water and transmit this to the arms 4, 5 of the windwheel, but for reasons of economy it is preferable to make it of thinner sheet metal 33 as illustrated and kept in shape by means of an angle iron frame work 95 attached to the sleeve 14 and to the arms 4, 5 of the wind wheel.

As shown in the drawings these supports 100 consist of an angle iron ring 35, (Fig. 2) to which the upper part of the sheet metal 33 is attached and which is in turn attached to the arms 4 of the wheel which serves the double purpose of keeping the upper part of the sheet metal circular and fastening it to the arms of the wheel. Angle iron ribs 105 34 attached to the above ring 35 prevents the sheet metal collapsing inwardly and conveys the pressure due to the weight of the windwheel downwards or otherwise conveys the upward pressure of the water to 110 the arms of the wheel and also transmits the pressure exerted by the wind from the vanes 1 through the arms 4 down to the bottom bearing 16 of the sleeve 14.

These ribs 34 may be strengthened in case 115 of large windmills by means of struts projecting inwardly towards the upper part of the sleeve 14 or the inner part of the arms 4 of the wheel.

The lower ends of these ribs 34 are fastened to the flanged ring 36 which is fastened to the flanged ring 37 screwed or otherwise fixed to the bottom of the sleeve 14.

The sheet metal 33 is fitted between the flanges of the rings 36 and 37 and the joint 125 is made water-tight by means of red lead, putty, india rubber insertion or such other suitable material.

In case it is preferred not to use the float F as such or in cases where it is desired to 130

take the weight of the windwheel as for instance when water has inadvertently gotten into the float F, or the cistern 8 is leaking, a bearing 38 with rollers or balls, such as 5 are in general use is placed immediately under the bearing 16 and above the upper end of a sleeve 39 fixed to the main frame 40 so as to take the weight of the windwheel as it rotates, and enable it to be used pending 10 repairs. In case the float is not required as such the cistern may be reduced in area and merely contain lubricating oil for the working parts.

When the windwheel is supported upon 15 the bearing 38 above the sleeve 39 the wind wheel cannot descend sufficiently for the effective use of the brakes in strong winds. It is necessary therefore to provide an additional brake for this purpose.

20 A suitable form of construction is shown in Fig. 8 and consists of a brake block 141 mounted on pivot 142, in such a position as to descend on the top of the cistern or a circular fixed rail 143 fixed thereto.

25 The block is normally held clear above the rail 143 by a counter balance weight 144 on an arm 145 of the brake, said arm being connected to arm 4 of the frame by a spring 146.

30 From the axis of arm 145 extends an arm 147 pivotally connected at 148 to a connecting rod 149 pivotally connected to a suitably guided sliding weight 150 adapted to slide on a horizontal radial rail 151.

35 During strong wind centrifugal force overcomes the weight of the counterbalance weight 144 and tension on spring 146 and weight 150 moves outwardly and causes the block 141 to bear upon the rail 143.

40 To prevent the access of rain dust or other material into the float F and cistern 8 a cover of sheet metal 41 is fastened to the float F immediately under the arms 4, and over rail 6 and its edge 41^a is turned down- 45 wardly to prevent rain being blown into the cistern.

The cistern 8 may be made of any suitable material and of any shape but it is made preferably of thin sheet metal 42 supported 50 in position and shape by an angle iron frame-work and is in shape conical corresponding to that of the float F.

The frame work consists of an angle iron ring 43 (Fig. 2) and ribs 44 which are 55 placed on the outside to prevent any obstruction to the circulation of the water inside and thus minimize the friction on the float F.

The jointing of the sheet metal 42 is 60 effected similarly to that of the float F except that the flanged ring 45 is on the inside and is bolted to the opposite flange 46 formed on the main supporting sleeve 39 of the fixed shaft 17 said flange 46 also 65 forming the bottom of the cistern 8.

The conical shape of the cistern 8 is preferable as it allows a freer circulation of the wind inside and through the wind wheel as the wind being deflected by the vanes 1 at different angles creates a kind of vortex 70 which assists the rotation of the wind wheel and a partial vacuum which occurs in the rear of the wind drum together with an uplift of the air currents due to the resistance of the structure renders the rear vanes 75 more effective when there is less obstruction offered by the cistern.

In order to increase the buoyancy of the water in the cistern 8 and so reduce the size 80 of both cistern and float, common salt or any other soluble compound of the alkali metals such as barium bromide, calcium bromide and the like may be added and in order to minimize or retard evaporation such salts as have an affinity for water may be added such as calcium chloride or barium chloride, furthermore for the latter objects the surface of the water may be covered with oil.

The sizes of the cistern and float should 90 be sufficient to carry the whole weight of the windwheel but where the prevailing winds or other conditions admit they may be made of any lesser size provided they are sufficiently high to maintain a sufficient reserve of lubricating oil in the sleeve 14 and thus save attention and risk on the part of attendants. In this case the cistern may be 95 entirely filled with oil.

When possible in place of a cistern any 100 natural or artificial water such as reservoirs or lagoons may be used in which case the windwheel would be mounted in same.

For the purpose of providing lubrication for the bearings 15, 16 that will last a long 105 time, the space between the fixed shaft 17 and the sleeve 14 is filled with oil and in order to provide for a longer supply the space above the upper bearing 15 may be enlarged or the space may be permanently 110 supplied by means of a storage cistern having a pipe connected with said space.

The sleeve 14 may be made of cast iron in one piece but as lightness with strength 115 are of importance it would be made of mild steel tubing in two pieces, joined by union flanges 92 (Fig. 4) the fixing bolts 93 passing through arms 4.

The rims 2 may be made in various ways but preferably from channel or angle iron 120 bars curved and fastened so as to form two concentric rings at a distance apart that would be suitable for attaching the vanes or sails 1.

The vanes or sails 1 are attached to the 125 rims 2 by means of brackets 50 made of sheet metal or light angle iron pressed into shape to suit the curvature of the vanes or sails one leg 51 of these brackets being horizontal and fastened to the rim rings 2 130

and the other leg being vertical and attached to the vanes.

The lower ends of the vanes or sails are fastened to a rim 52 which in the case of 5 small windmills is best made of segments of sheet metal suitably joined to which the vanes are attached by means of brackets similar to those described for attaching the vanes to the upper rim 2. In large wind- 10 mills the lower rim 52 would be made of angle iron similar to but lighter than the upper rim 2 similar brackets being used.

The vanes 1 are set at an angle of between 30° and 40° to radii of the wind- 15 wheel and are bent horizontally to the form of a parabolic curve the apex edge of which is disposed outwards and the base edge inwards.

This curvature is maintained by the brac- 20 king pieces of sheet metal 3 cut and bent to the same curvature as the vanes and fastened in between the vanes by screws or rivets or soldered as in Fig. 5. These sheet metal braces 3 are also to be set at an angle 25 so that a series of them will form a spiral reaching from the bottom rim 52 to the top rim 2 and so transmit the pressure received from the wind upwards to the arms 4 and 5 of the windwheel.

30 In addition and to prevent torque of the vanes 1 in strong winds certain vanes at intervals and preferably those immediately below the arms of the windwheel are made of extra strong sheet metal and are braced 35 diagonally from the bottom of each to the arms 4 on both sides near the ends by means of curved and inclined light iron rods or stout wires 53 (Fig. 5) as may be necessary.

40 When the windwheel rotates a proportion of the vanes or sails must be always coming up against the wind and those in front will present surfaces that are curved backwards from it and those in the rear 45 will be coming up mostly edge on to it, while this back pressure is of little importance in districts where the winds are strong and constant it is otherwise where they are not and for this reason a rotary wind screen 54, 55 is provided.

This wind screen is mounted on a framework 56 which is pivoted on a shouldered seating 57 on the sleeve 39 immediately under the cistern 8 and is provided with three 55 or more wheels 58 that run on a circular rail 59 concentric with the windwheel and supported on the main frame 40.

Attached to the frame work 56 and remote from the screen is a vane 157 similar 60 to those of the annular type of windmill in general use and set at such an angle as to bring the wind screens properly into position to screen the vanes 1 moving to windward.

65 The wind screen itself consists of the two

walls or parts 54, 55, curved parallel to the vanes, the former of which is on the outside of the vanes and projects upwardly so as to protect the vanes in front, and the other part 55 is on the inner side of the vanes 70 and projects upwardly so as to protect the on-coming vanes further back from inside. The screens are made of sheet metal fastened to angle iron supports 60 and the frame work 56 is made of angle iron of suitable cross-sectional area and suitably struttured.

I claim:—

1. A windmill comprising a fixed vertical shaft, a cistern surrounding the latter, a 80 float in the cistern rotatably mounted on said shaft, and a horizontal wind wheel carried by the float and surrounding the cistern.

2. A windmill comprising a hollow stationary shaft, a shaft rotatable in the latter, a cistern surrounding the shafts, a sleeve in the cistern rotatably mounted on the fixed shaft, a float carrying the sleeve and a horizontal wind wheel carried by the sleeve 90 and surrounding the cistern.

3. A windmill comprising a hollow stationary shaft, a shaft rotatable in the latter, a cistern surrounding the shafts, a sleeve in the cistern surrounding the shafts, bearings 95 mounted in the sleeve rotatable on the stationary shaft, rods adjustably connecting the bearings, a float carrying the sleeve, and a horizontally disposed windwheel carried by the latter.

4. A windmill comprising a frame, a cistern mounted therein, a shaft extending axially through the cistern, a sleeve rotatable on the shaft, a float carrying the sleeve, a horizontally disposed windwheel carried by the latter, a crank-pin carried by the wheel, a vertically reciprocable rod, and actuating mechanism connecting the latter with the crank-pin. 105

5. A windmill comprising a frame, a 110 cistern mounted therein, a stationary shaft extending axially through the cistern, a sleeve rotatable on the shaft, a float carrying the sleeve, a horizontally disposed windwheel carried by the latter, a central rotatable shaft connected with the sleeve, a crank-disk mounted on the central shaft, a pump rod, and actuating mechanism connecting the latter with the crank disk.

6. A windmill comprising a hollow stationary shaft, a shaft rotatable in the latter, a cistern surrounding the shafts, a sleeve in the cistern rotatable on the fixed shaft, a float connected to the sleeve, a horizontally disposed wind wheel carried by the latter, a 125 crank pin on the wheel, a vertically reciprocable rod, a bell-crank lever connected with the latter, and a rod connecting the crank-pin and bell crank lever.

7. A windmill comprising a cistern, a 130

fixed shaft projecting through the latter, a sleeve rotatable on the shaft, a float carrying the sleeve, annular horizontal wheel elements connected with and carried by the sleeve, vertically disposed vanes mounted on the annular members, and wind shields arranged concentrically to the annular members on opposite sides of the vanes.

8. A windmill comprising a frame, a conical cistern mounted thereon, a fixed hollow shaft projecting axially through the cistern, a sleeve in the cistern rotatably mounted on and movable axially of the shaft, a conical float surrounding the sleeve and fixed to the lower end of the latter, a horizontally disposed wind wheel connected to the upper end of the sleeve, said wheel including a plurality of vertically arranged vanes, and wind shields arranged concentrically to the axis of the wheel adjustably mounted on the frame.

9. A windmill comprising horizontally disposed annular members, radial supports therefor, a rotatable and axially movable carrier for the supports, vertically disposed vanes carried by the annular members, and spirally arranged braces connecting the vanes.

10. A windmill comprising a float, a rotatable and axially movable member carried thereby, a plurality of radial supporting members carried by the rotatable member, horizontally disposed annular frame members carried by the supporting members, vertically disposed vanes depending from the latter, and spirally arranged metal plates connecting the vanes.

11. A windmill comprising a cistern, a stationary shaft projecting axially through

the latter, a sleeve rotatable and axially movable on the shaft, a float connected to the sleeve, radial arms projecting from the latter, a circular rail carried by the arms, brake member, arranged to engage the rail, and a plurality of vertically disposed vanes carried by the radial arms.

12. A windmill comprising a cistern, a float rotatable and axially movable therein, a plurality of radial arms carried by the float, a series of vanes carried by the said arms, a circular rail fixed to the underside of the latter, and brake blocks mounted beneath and adapted to engage the rail.

13. A windmill comprising a cistern, a float rotatable and axially movable therein, a plurality of radial arms carried by the float, a series of vanes carried by said arms, a wind screen for said vanes movable about the axis of the cistern, and a vane on the screen.

14. A windmill comprising a cistern, a float rotatable and axially movable therein, a plurality of radial arms carried by the float, an annular series of vertically disposed vanes carried by the arms, curved plates mounted on opposite sides of the series of vanes, and a frame supporting the plates adapted to move them concentrically to the series of vanes.

15. A windmill comprising a cistern, a conical float rotatable and axially movable therein, a horizontally disposed wind wheel carried by the float, and blades on the periphery of float for retarding the rotation of the latter.

Dated this fifth day of October 1922.

ROLAND ROLF RICHARD.
